ELECTRIC WATER HEATER

Filed Sept. 26, 1922

2 Sheets-Sheet 2

FIG. 4.

Patented Mar. 22, 1927.

UNITED STATES PATENT OFFICE.

ALPHONSE MARTIN, OF OGDENSBURG, NEW YORK, ASSIGNOR OF FIFTY-ONE ONE-HUNDREDTHS TO MAX KATZMAN, OF OGDENSBURG, NEW YORK.

ELECTRIC WATER HEATER.

Application filed September 26, 1922. Serial No. 590,584.

This invention relates to an electric water heater in which the water to be heated is allowed to flow into the lower end of an upright container where it is heated by direct contact with a plurality of pairs of electrodes supported in superposed relation by suitable conductors from the top of the container which has a suitable discharge nozzle for the escape of the heated water.

5 The main object is to electrically heat a suitable body of water in a container to a pre-determined degree of temperature and to automatically maintain approximately that temperature for indefinite periods of time by the use of a relatively small amount of electric current within a pre-determined maximum amperage. Another object is to distribute the heating units in such manner as to render the waste or wear of the electrodes of the several heaters practically negligible.

Other objects and uses relating to specific parts of the apparatus will be brought out in the following description.

25 In the drawings:

Figs. 1 and 2 are respectively a top plan and a side elevation of an electric water heater embodying the various features of my invention, the controlling valve being omitted in Fig. 1.

Fig. 3 is a detail sectional view of the thermostatic switch taken on line 3-3, Fig. 1.

Figs. 4 and 5 are longitudinal vertical sectional views taken respectively on lines 4-4 and 5-5, Fig. 1.

As illustrated this water heater comprises an upright cylindrical shell 1 having lower and upper end heads 2 and 3 rigidly secured to the adjacent end of the shell 1 to form liquid-tight joints therewith for producing an upright container which is elongated vertically.

The lower end or head 2 is provided with a water inlet 4 to which is connected a supply pipe 5 having a valve 6 adapted to be operated by hand for controlling the supply of water through the inlet to the container and also serving to control the supply of heated water through

50 outlet.

The upper end or end head 3 is pro-

vided with an outlet 7 to which is connected an external discharge nozzle 8, the outlet and discharge nozzle being preferably located at one side of the axis of the container while the outer end of the discharge nozzle is deflected downwardly at the outside of the container for convenience of delivery into an underlying receptacle.

60

Heater.

The upper end head 3 of the container is provided with a central circular opening 9 for receiving a bushing 10 which is removably secured in place by screws 11 for receiving and supporting a pair of upright electric conductors 12 in parallel spaced relation centrally within the conductor 1.

The conductors 12 preferably consist of round rods of copper or other suitable material having their upper ends reduced in diameter and extending through and above the bushing 10 to form terminals or binding posts 13 which are adapted to be connected in an electric heating circuit through the medium of flexible cables 14 having a terminal plug 15 for engagement in any ordinary floor or wall socket of the usual incandescent lighting circuit.

These conductors 12 are insulated from the bushing 10 by insulating sleeves 16 and are tightly clamped in place by nuts 17, the terminals 13 being additionally insulated from the bushing 10 by an insulating cap 18 having apertures through which the terminals extend for engagement by a slip connection 19. The conductors 12 extend into the container approximately half the length thereof and their inner ends at one side are preferably recessed to form substantially flat faces 20 and shoulders 21 for receiving the adjacent ends of another pair of vertical conductors 12' which form extensions of the conductors 12 and have their upper ends secured to the conductors 12 by screws 22 while their lower ends extend to points relatively near the lower end heads 2.

These conductors 12' are half-round

in cross section and are arranged in parallelism with their flat faces at the same side for receiving and supporting a plurality of, in this instance, five spring clasps or loops 5 —23— which are secured by spot-welding or otherwise secured to the flat sides of the extensions —12— with their open sides at the top for receiving and supporting a corresponding number of cylindrical electrodes 10 —24— preferably of carbon.

Each conductor —12— is provided with the same number of spring clips —23—, those of each bar being arranged in space relation one above the other and directly opposite and in axial alignment with those of the other bar so that the electrodes or both bars will be arranged in pairs while those of each pair will be arranged in slightly spaced relation endwise to form intervening gaps 15 for producing electric heat for heating the water in the container.

The clips —23— are tensioned to frictionally hold the electrodes —24— of each pair in proper relative position for producing the 20 desired arcs and may also be sprung open by hand to release the electrodes when desired to remove them or for readjustment, the outer ends of the electrodes being preferably enlarged to prevent the adjacent ends from 25 contacting with each other.

A spacing block —25— is secured to the lower ends of the conductor rods —12 and 12'— in spaced relation aided by the abutting of the upper ends of the lower rods 30 —12— with the shoulders —21—.

Thermostat control.

In Figs. 3-4-5 is shown a thermostatic electric switch consisting of a thermostatic bar —26— carrying a contact member 40 —27— which is normally in contact with a cooperative contact member —28— on the adjacent end of a resilient bar —29— when the temperature of the container produced, by the water therein is below a certain degree but is adapted to be open by the deflection of the bar —26— when the temperature of the container exceeds that degree. These bars —26 and 29— and their contact 45 members —27 and 28— constitute an electric switch and are secured to terminals —30— which in turn are mounted in an insulating block —31— in spaced relation so that the upper ends of the terminals may extend beyond the insulating block while the bars —26 and 29— and their contact members 50 —27 and 28— extend some distance below said block.

This insulating block —31— is secured to 55 the outer side of the cylindrical shell —1— by means of a screw —32— and together with the bars —26 and 29— and contact members —27 and 28— are inclosed in a removable house or cover section —33— which is

secured by screws —34— to the insulating block —31—.

A slip connection —19— is connected to the cables —14— and to the connection —19— for detachable engagement with the terminals —30— for connecting the thermo-electric switch in the heating circuit whereby the heat developed in the container by the energizing of the electrodes —24— will automatically control the temperature of the water in the container said switch being 75 preferably adjusted to keep the temperature of the water below the boiling point, although it is evident that the critical temperature may be varied at will by simply adjusting the contact members —27— and 80 —28— relatively to each other.

Operation.

When the container —1— is once filled with water it will always remain filled by 85 reason of the fact that the outlet is at the upper end while the inlet is at the lower end and when the thermo-electric switch is properly adjusted it will normally close the heating circuit through the several pairs of electrodes until the temperature of the water reaches a pre-determined degree of say 212° F., and at about this temperature the thermostatic switch will be automatically opened by imparting the heat of the water to the 90 thermostatic bar, the ebullition taking place at the gaps between the adjacent ends of the electrodes of each pair.

That is, the water surrounding the electrodes causes a relatively thin film to pass 100 between the electrodes and this thin film of water is quickly heated and rises to the surface and is continually replaced by the cooler water until the whole body is heated to the desired temperature when the heating 105 circuit is broken by the opening of the thermo-electric switch.

On the other hand if the temperature of the water is reduced below that degree, the thermostatic switch will automatically close 110 the heating circuit to restore the temperature of the water so that the latter is always retained at the desired temperature ready for immediate use to an amount equal to the capacity of the container by simply opening the valve —6— which capacity is usually regulated according to the number of heating 115 units employed.

I claim:

1. In an electric water heater, a pair of upright conductors, each provided with a plurality of vertically spaced electrodes having their axes extending horizontally, the electrodes of each conductor being arranged in axially opposed spaced relation to those of the other conductor to form vertical watergaps between adjacent ends of opposed electrodes.

2. An electric water heater as in claim 1 in which the water-gaps between the horizontally opposed electrodes are disposed in substantially the same vertical plane between the conductors.

3. An electric water heater comprising an upright water container, upright electric conducting bars supported from the top of

the container in parallel spaced relation, spring-clasps mounted side by side upon the bars in transverse alignment, and electrode members frictionally held by the clasps.

In witness whereof I have hereunto set my hand this 18th day of September 1922.

ALPHONSE MARTIN.
